UNITED STATES PATENT OFFICE.

SHOZO ASAKAWA, OF KANAGAWA-KEN, JAPAN.

SHIP CONSTRUCTION.

1,313,663.

Specification of Letters Patent. Patented Aug. 19, 1919.

Application filed April 16, 1918. Serial No. 228,861.

To all whom it may concern:

Be it known that I, SHOZO ASAKAWA, a subject of the Emperor of Japan, and residing at No. 105 Suzaki, Uraga, Kanagawa-
5 Ken, Japan, have invented certain new and useful Improvements in Ship Construction, of which the following is a specification.

This invention relates to ships and is particularly directed to improvements in the 10 hulls thereof. The improvements are especially provided in order to eliminate certain material and the expense incident to the assemblage thereof. By my construction I am enabled to obtain greater 15 storage space for the cargo, and increased stability without affecting the strength or rigidity of the hull.

One of the objects of my invention is to improve the hulls of vessels having cellular 20 double bottoms, and this I accomplish by substituting vertical bars for the horizontal longitudinal frames now used. Generally, therefore, my invention consists in combining a double bottomed hull having 25 longitudinal beams, with vertical side bars which extend upwardly from the bottom of the hull and form the skeleton frame for the sides of the ship.

With the foregoing object outlined and 30 with other objects in view, which will appear as the description proceeds, my invention consists in the novel features herein-
after described in detail, illustrated in the accompanying drawings and more partic-
35 ularly pointed out in the appended claims.

Referring to the drawings:

Figure 1, is a transverse vertical sectional view of a portion of the bottom and side of a ship's hull constructed in accordance with 40 my invention.

Fig. 2, is a transverse horizontal sectional view of the same.

In detail:

In Figs. 1 and 2 of the drawings B, represents the bottom of a vessel constructed in 45 accordance with my invention and including vertically disposed longitudinal keel bars 8, 9 and 10 which preferably extend the full length of the vessel. These bars 50 are spaced apart the necessary distance and are connected together by series of vertical transverse plates, 6, the connection of the plates and bars being made by means of angle irons 13, which are vertically dis-

posed. The plates 6 are also connected together by means of longitudinally disposed angle irons 11 and 12 and are provided with apertures 14 to reduce their weight. Extending from the plate 10 are vertical transverse gusset plates 4, which correspond in number to the rows of plates 6 and are connected at their lower ends to the plates 4, are vertically extending angle irons 2, which are secured to reversely placed angle irons 1, to form the side ribs of the hull. 65 Resting on the upper edges of the plates 6 and upper surfaces of the bars 11 is the floor plating 7. The outer plating 3 of the hull is connected to the lower bars 12 and to the angle irons 1. A longitudinally extending 70 angle bar 5 is used in connecting the bar 10 to the outer plating of the vessel.

With the old well known construction employing only longitudinal frames it will be seen that a multiplicity of longitudinal 75 plates and bars are used in forming the sides of the ship and that these members extending inwardly occupy a large portion of the interior of the hull and consequently the cargo space is reduced thereby. The plates 80 4¹ also form shelves upon which damp material may collect and this accumulated material will cause the plates to rot and thus affect the rigidity of the hull. By my construction I am enabled to increase the cargo 85 space, eliminate a great deal of material, and reduce the cost of construction.

In Figs. 1 and 2 I have shown the upper deck 15 and lower deck 16 but as the decks form no part of my invention it will not 90 be necessary to describe the same.

What I claim and desire to secure by Letters Patent is:

1. In a ship, the combination with a double bottom having longitudinal bars extending substantially the entire length of the vessel and transverse intercostal short bars connecting the same, of longitudinal shell and inner bottom plating connected to said bars, and a side framing formed only of 100 vertically extending bars having their lower ends connected to said double bottom in the way of the intercostal bars.

2. In a ship, the combination with a double bottom having longitudinal bars extending substantially the entire length of the vessel and transverse intercostal short bars arranged between the longitudinal bars, of 105

longitudinal shell and inner bottom plating connected to said bars, and a side framing formed only of vertical angle bars which correspond in number to the transverse bars 5 and have their lower ends secured to said double bottom in the way of the intercostal bars.

In testimony whereof I have hereunto set my hand in presence of two subscribing witnesses.

SHOZO ASAOKAWA.
